UNITED STATES PATENT OFFICE.

ORANGE G. ROMIG, OF AKRON, OHIO, ASSIGNOR OF ONE-HALF TO T. KOLINS, OF AKRON, OHIO.

LAWN MOWER.

Application filed October 25, 1923. Serial No. 670,779.

To all whom it may concern:

Be it known that I, ORANGE G. ROMIG, a citizen of the United States, and resident of Akron, Ohio, have invented new and useful Improvements in Lawn Mowers, of which the following is a specification.

My invention relates to lawn-mowers and it has, for its primary object, a particular type of construction of the above designated machines which shall facilitate the sharpening of the cutting blades.

It is well known, of course, that the blades of lawn-mowers may be sharpened by interchanging certain parts in order to provide for rotation of the blades in an opposite direction to their normal movement, whereby abrasive material may be disposed upon the stationary cutting blade and the rotating blades operated to effect a grinding and sharpening action. However, such method of operation requires so much time and trouble that it is not particularly desirable from a practical standpoint. Consequently, one of the principal objects of my invention is to provide a lawn-mower of such construction that the rotation of the cutting blades may be reversed by a simple manipulation of certain added parts of such character as to require very little time.

It is true lawn-mowers have been especially constructed to provide for sharpening the blades thereof by means of reversing their direction of rotation, but it appears that such constructions are of such character as to necessitate a material departure from standard designs. Consequently, standard lawn-mowers may not be adapted to be changed to such an extent as to conform with the structures proposed and as a result only new mowers may be provided with the necessary devices.

Another object of my invention is to provide means for reversing the direction of rotation of the blades of a lawn-mower by a simple change in the standard design of any machine, which may be accomplished with very little expense and labor.

With these and other objects in view, my invention will be more fully described, illustrated in the drawings, and then fully pointed out in the appended claims.

In the drawings:

Fig. 1 is a view, partially in elevation and partially in section, of the principal parts of a lawn-mower to which my im-

proved construction is applied in order to accomplish the purpose of the invention;

Fig. 2 is a sectional view of one end of a blade-supporting spindle and a gear therefor which is especially adapted to secure 60 rotation of the spindle selectively in two directions;

Fig. 3 is an end view of a gear utilized in a lawn-mower that is especially constructed in accordance with my invention; 65

Fig. 4 is a sectional view taken along the line IV—IV of Fig. 2;

Fig. 5 is another sectional view taken along the line V—V of Fig. 2; and

Fig. 6 is a detail view of a modified form 70 of blade-supporting spindle and attachments therefor to accomplish the purpose of the invention, which is illustrated in the preceding figures.

In practicing my invention a standard 75 lawn-mower may be changed slightly to secure rotation of the blade-carrying spindle in two directions by drilling openings of suitable depth in the ends of the blade-supporting spindle. A transverse slot is also 80 cut through the spindle adjacent each end and a spring is inserted in each of the openings to engage a cylinder disposed therein, which is provided with a slot adapted to register with the corresponding one in the 85 end of the spindle. Each end of the spindle is interiorly threaded to provide for the reception of a threaded plug, which controls the position of the cylinder and thereby regulates the position of a key disposed 90

through the slot of the spindle and that of the cylinder. The gear ordinarily mounted upon each end of the spindle, has a tubular shank or extension which has a series of ratchets faced in one direction 95 whereby rotation of the spindle is secured in only one direction by engagement of the gear with the driving wheels. The tubular extending portion of the gear may be provided with an additional extension having 100 another series of ratchet members faced in the opposite direction to those normally formed thereon. The key projecting

through the spindle at each end thereof engages one or the other of the series of 105 ratchet members on the gear, whereby rotation of the spindle is secured in one direction or the other, according to the position of the key, which position is easily regulated by manipulation of the threaded 110

2 member disposed in the opening provided in each end of the spindle.

A better understanding of my invention may be had by a reference to the drawings, in which only the main parts of a lawn-mower are shown, since my invention is particularly concerned with the mounting of the driving gears upon the blade-supporting spindle, the remaining portion of the construction being of any standard design.

As will be seen in Fig. 1, the lawn-mower includes a plurality of driving wheels 1 provided with internal racks 2 adapted to mesh with a gear 3 at each end of a spindle 4, whereby the spindle is driven when the wheels are forced over the ground. In order to accomplish the purpose of my invention, the spindle 4 is provided with a longitudinal opening 5 at each end, into which springs 6 are inserted to engage the end walls of the openings and cylinders 7, each of which is provided with a slot 8 adapted to register with an elongate transverse slot 9 adjacent each end of the spindle. The spindle 4 is internally threaded at each end to provide for the reception of threaded plugs 10 that are inserted therein to engage the cylinders 7 and regulate their positions against the action of the springs 6 to thereby properly adjust keys 11 disposed through the slots 8 and 9. One of the gears 3 is mounted upon the exterior surface at each end of the spindle 4 and is provided with tubular extensions 13 having two sets of ratchet members 14 and 15, which are faced in opposite directions, as will be clearly seen in Fig. 3.

In operating a lawn-mower to secure the benefit of my invention from the construction above described, the plug 10 is normally in such position that the key 11 engages one of the series of ratchets 14 whereby normal operation of the blades upon the supporting spindle 4 is secured. However, when it is desired to sharpen the blades the plug 10 is screwed into the spindle 4 to force the cylinder 7, against the action of the spring 6, towards the center of the spindle whereby the key 11 engages only the second set of ratchet members 15. The operating position of the lawn-mower may then be reversed and the spindle operated in a reversed direction by pushing the mower forward to operate the driving wheels 1. It is apparent, of course, that the manipulation of the plug 10 is effected at both ends of the spindle 4 and that the construction is similar in each end. It will be understood, of course, that the lawn-mower is ordinarily so constructed that the blades normally operate in only one direction and, for example, when the lawn-mower is operated in a reverse direction, the blades remain stationary. The invention provides for the operation of the blades in both directions by an adjustment

of the device hereinbefore described to select the proper ratchet members to obtain the desired motion. To secure sharpening of the blades, it is only necessary to apply an abrasive compound thereto after the parts have 70 been adjusted as above described.

In Fig. 6 a slight modification of my invention is illustrated which embodies exactly the same principle as the preferred form, but which is realized in a slightly different 75 manner. In this instance, a tubular spindle 16 is utilized, which is provided with an elongate slot 17 adjacent each end thereof, and a plurality of rods 18 are disposed within the spindle that are also provided with 80 slots adapted to register with those in the spindle. Keys 19 are disposed through the rods 18 and the spindle 16, as in the preferred construction. However, adjustment of the rods 18 and consequently, of the keys 85 19 is secured by a somewhat different construction. A spring 20 is disposed in each end of the spindle 16 in engagement with an adjacent rod 18 and a threaded plug 21. A wedge member 22 is disposed through a 90 suitable opening in substantially the center of the spindle 16, engaging the rods 18 and forcing them outwardly against the action of the spring 20 to position the keys 19 in 95 engagement with the inner set of ratchet members of the gears 3. The wedge is provided with a central opening adapted to register with an opening in the spindle 16, through which a pin 23 may be disposed to maintain the wedge 22 in its normal position.

When it is desired to reverse the rotation of the gears 3 in this construction, the pin 23 is removed and the wedge 22 is withdrawn to permit the springs 20 to force the rods 18 inwardly toward the center of the spindle 16 and effect an engagement of the keys 19 with the outer ratchet members 15 of the gears 3.

It will be seen from the foregoing description, that a newly constructed lawn-mower may be provided with a simple attachment for driving the cutting blades in both directions in order to facilitate the sharpening thereof, or lawn-mowers of standard design that have been in service for some time may be disassembled and easily provided with the simple devices necessary to accomplish the purpose of my invention. My invention possesses desirable advantages not only by reason of the fact that it may be applied to lawn-mowers of standard construction that have been in service, but also by reason of the fact that it adds very little to the expense of production of a new mower in order to attain decided advantages over the usual type of construction.

Although I have shown and specifically described a preferred form and modification thereof, it will be understood that my inven-

tion is not limited thereby, but constructions embodying the same principle may be utilized by effecting slight changes without departing from the spirit and scope of my invention, and I desire, therefore, that no limitations shall be imposed except such as are indicated in the appended claims.

What I claim is:

1. In a lawn-mower, the combination with 10 a plurality of driving wheels and a rotatable blade-supporting spindle, of gears mounted upon the spindle in operative relation to the driving wheels, said gears being provided with two sets of oppositely faced 15 ratchet members and adjustable means for selectively engaging the ratchet members.

2. In a lawn-mower, the combination with 20 a plurality of driving wheels and a rotatable blade-supporting spindle, of gears mounted upon the spindle in operative relation to the driving wheels, said gears being provided with tubular extensions having 25 two series of oppositely faced ratchet members and adjustable means for engaging the ratchet members.

3. In a lawn-mower, the combination with 30 a plurality of driving wheels, of a rotatable blade-supporting spindle provided with elongate slots, keys adjustably mounted in the slots and a gear mounted upon each end of the spindle in operative relation to the driving wheels, said gear having oppositely faced ratchet members adapted to be selectively engaged by the corresponding key.

4. In a lawn-mower, the combination with 35 a plurality of driving wheels, of a rotatable blade-supporting spindle having a threaded longitudinal opening in each end and provided with a transverse slot adjacent each 40 end, a cylinder disposed in each opening having a slot adapted to register with the corresponding slot in the spindle, a key disposed in the slot at each end of the spindle through the slot of the cylinder, means for 45 maintaining the cylinder in adjusted position and a gear mounted upon each end of the spindle in operative relation to the driving wheels, said gear having oppositely faced ratchet members adapted to be selectively engaged by the corresponding key.

5. In a lawn-mower, the combination with 50 a plurality of driving wheels of a rotatable blade-supporting spindle having a threaded

longitudinal opening in each end and provided with a transverse slot adjacent each 55 end, a cylinder disposed in each opening having a slot adapted to register with the corresponding slot in the spindle, a key disposed in the slot in each end of the spindle through the slot of the cylinder, a 60 spring disposed in each opening in engagement with the cylinder and the end wall of the opening, a threaded member screwed into the opening to engage the cylinder and a gear mounted upon each end of the spindle 65 in operative relation to the driving wheels, said gear having a tubular extension provided with two sets of interiorly located oppositely faced ratchet members adapted 70 to be selectively engaged by the corresponding key by manipulation of the threaded member.

6. In a lawn-mower, the combination with 75 a plurality of driving wheels, of a tubular rotatable blade-supporting spindle provided with an elongate slot adjacent each end, a plurality of rods each having a slot adjacent one end disposed in the spindle, a key adapted to fit in the slot of each rod and project through a registered slot of the 80 spindle, means for maintaining the rods in adjusted position comprising a plurality of springs and a centrally located wedge member and a gear mounted upon each end of the spindle having two series of ratchet 85 members adapted to be selectively engaged by the corresponding key according to the position of the rods.

7. In a lawn-mower, the combination with 90 a plurality of driving wheels and a rotatable blade-supporting spindle, of gears mounted upon the spindle in operative relation to the driving wheels, said gears being provided with contiguous sets of oppositely faced ratchet members, keys adjustably 95 mounted upon the spindle to engage the ratchet members of the gears and means for maintaining the keys in engagement with a selected set of the ratchet members.

In witness whereof, I have hereunto 100 signed my name in the presence of two subscribing witnesses.

ORANGE G. ROMIG.
